COMPOSITIONS OF FLUOROCARBONS

Robert D. Broadley, Hanover Township, Morris County, N.J., and Lyman F. Kells, New York, N.Y., assignors to Allied Chemical Corporation, New York, N.Y., a corporation of New York

No Drawing. Filed Mar. 12, 1962, Ser. No. 179,236

2 Claims. (Cl. 252—67)

This invention relates to fluorinated hydrocarbons, and more particularly to constant boiling fluorocarbon mixtures which comprise difluoromethane and perfluoropropane and which are especially adapted for use as high capacity, low temperature refrigeration compositions.

The refrigeration capacity of a given amount of refrigerant is largely a function of boiling point, the lower boiling refrigerants generally offering the greater capacity at a given evaporator temperature. This factor to a great extent influences the design of refrigeration equipment and affects capacity, power requirements, size and cost of the unit. Another important factor directly related to boiling point of the refrigerant is minimum cooling temperature obtained in the evaporator during the refrigeration cycle, the lower boiling refrigerants being used to achieve the lower refrigeration temperatures. For these reasons a large number of refrigerants of different boiling temperature and capacity are required to permit flexibility in design, and the art is continuously faced with the problem of providing new refrigerants as the need arises for new capacities and types of installations.

The lower aliphatic hydrocarbons when substituted by chlorine and fluorine are well known to have potential as refrigerants. Many of these chlorofluorohydrocarbons exhibit certain desired properties including low cost, low specific volume, low toxicity and chemical inertness which have resulted in the extensive use of such compounds in a large number of refrigeration applications. Examples of such compounds include difluorodichloromethane, B.P. —29.8° C., chlorodifluoromethane, B.P. —40.8° C., fluorodichloromethane, B.P. 8.9° C., fluorotrichloromethane, B.P. 23.8° C., and tetrafluorodichloroethane, B.P. 3.5° C. While these chlorine-fluorine derivatives provide an adequate range of refrigerants for many purposes, only a very few boil sufficiently low to offer any potential as low temperature refrigerants. A major reason for this is the presence of the heavier chlorine substituent which generally results in a higher boiling compound than those containing predominantly fluorine or hydrogen.

A compound having considerable potential as a low temperature refrigerant is difluoromethane, B.P. —51.6° C. This fluorocarbon possesses many of the desired properties for use in refrigeration notwithstanding the presence of 2 hydrogen atoms which tend to induce flammability which may be objectionable in some refrigeration applications. While fluorocarbons of this type are low boiling, the limited number of such compounds having the desired refrigerant properties represent widely different boiling points and fail to provide a satisfactory range of low boiling refrigerants of different capacity.

Increased activity in the field of cryogenics and low temperature refrigeration gives rise to a need for new low temperature refrigerants representing different capacities than now available. An object of the present invention is to provide new low temperature compositions especially suitable for use as refrigerants. More particularly, it is an object to provide new refrigerants boiling lower and having greater capacity than the low boiling difluoromethane. Another object is to provide new low boiling compositions composed of difluoromethane mixtures which are useful in producing refrigeration in those systems in which cooling is achieved by evaporation in

2

the vicinity of the body to be cooled. A further object is to provide low boiling difluoromethane compositions in which the flammability is reduced to substantially negligible proportions.

In accordance with the invention it has been discovered that compositions consisting of difluoromethane and approximately 10 mole percent to 62 mol percent perfluoropropane (C_3F_8), B.P. —37.0° C. form a mixture system of liquid compositions which have a boiling temperature of about —58.1° C. These difluoromethane-perfluoropropane compositions with the —58.1° C. boiling temperature represent a marked reduction as compared with the boiling temperature of the lower boiling difluoromethane component. The indicated difluoromethane-perfluoropropane compositions provide substantially increased refrigeration capacity and represent new refrigerant compositions useful in obtaining high capacity low temperature refrigeration. Further, flammability of difluoromethane is reduced by admixture with perfluoropropane such that all compositions within the indicated range are substantially non-flammable.

Boiling points of difluoromethane-perfluoropropane mixtures were determined experimentally using difluoromethane and perfluoropropane each better than 99.9% pure. Difluoromethane-perfluoropropane mixtures of known composition were prepared and boiling points were measured in a vacuum jacketed boiling point tube under Dry Ice-acetone reflux. Temperatures were measured using a platinum resistance thermometer, and all determinations run in duplicate. The experimentally determined boiling points were corrected to a normal atmospheric pressure of 760 mm. of Hg and are summarized below:

TABLE I

Normal boiling points of CH_2F_2/C_3F_8 mixture system	
Mol percent C_3F_8 in solution:	Normal boiling point, —° C.
0.0	—51.60
1.7	—53.50
9.9	—58.10
19.5	—58.13
25.4	—58.10
38.5	—58.07
61.7	—58.08

The data demonstrate that compositions consisting of difluoromethane and about 10 mol percent to 62 mol percent perfluoropropane have the same boiling temperature of about —58.1° C. The presence of a broad range of compositions having the same boiling temperature of —58.1° C., representing a relatively marked depression of about 6.5° C. over that of the low boiling difluoromethane component, indicated the difluoromethane and perfluoropropane were only partially miscible within the indicated range and formed compositions having two liquid phases. Examination of the 9.9 mol percent and 61.7 mol percent perfluoropropane compositions showed the presence of two liquid phases and confirmed the formation of a two-liquid phase system, while examination of the 1.7 mol percent perfluoropropane composition showed only a single liquid phase. We find that when the two liquid phases are present, the entire range of compositions consisting of difluoromethane and approximately 10 to 62 mol percent perfluoropropane will boil at a substantially constant temperature and give a constant vapor composition for the two-liquid phase compositions described.

Apart from use of the indicated amounts of difluoromethane and perfluoropropane make-up of the compositions of the invention requires no special procedures. The difluoromethane and perfluoropropane employed

should be substantially pure, preferably at least about 99.0 percent pure, and contain no substances deleteriously affecting the boiling characteristics of the mixture compositions or use as refrigerants.

The minimum boiling two-liquid phase mixture system formed between difluoromethane and perfluoropropane provides a broad range of mixture compositions which boil at substantially constant temperature and give a constant vapor composition. These two-liquid phase mixtures differ from refrigerant mixtures proposed in the past which offer only a relatively narrow range of useful compositions. While prior mixtures boil generally only about 1-3° C. below the lower boiling component, the mixture system of the present invention results in a relatively large reduction of about 6.5° C. over the boiling point of difluoromethane. The compositions of the invention may be used in design of refrigeration equipment of reduced size operating at the evaporator temperatures of about minus 15 and below to e.g. minus 70-80° C.

The compositions of the invention exhibit desired refrigeration properties including low toxicity, chemical inertness, and substantial non-flammability. In addition to being useful as new refrigerants providing high ca-

pacity low temperature refrigeration it will be noted that the mixtures disclosed herein may also be used for other purposes including a heat transfer medium, gaseous dielectric, low temperature solvent and power fluid.

5 We claim:

1. A low boiling composition consisting of a mixture of difluoromethane and perfluoropropane, in which the mol percent of perfluoropropane is within the range of about 10-62.
- 10 2. The process of producing refrigeration which comprises condensing a mixture consisting of difluoromethane and perfluoropropane in which the mol percent of perfluoropropane is within the range of about 10-62, and thereafter evaporating said mixture in the vicinity of a body to be cooled.
